UNITED STATES PATENT OFFICE.

WILLIAM E. YERKS, OF YONKERS, NEW YORK.

LUMBER-JACK.

1,071,198.

Specification of Letters Patent. Patented Aug. 26, 1913.

Application filed December 15, 1911. Serial No. 663,075.

To all whom it may concern:

Be it known that I, WILLIAM E. YERKS, a citizen of the United States, and a resident of Yonkers, in the county of Westchester 5 and State of New York, United States of America, have invented certain new and useful Improvements in Lumber-Jacks, of which the following is a specification.

My invention relates to an improved device for handling lumber which I have called a lumber jack, and its object is to overcome the defects in and to improve upon such devices of this character as have heretofore been known, and to provide a 15 simple and inexpensive device by means of which lumber may be moved and stacked with great facility.

I will describe my invention in the following specification and point out the novel 20 features thereof in appended claims.

Figure 1 is a side elevation of a lumber jack made according to my invention and shows also the manner in which it is used. Fig. 2 is a plan view of parts shown in Fig. 25 1. Fig. 3 shows an elevation of the rotatable contact head and the upper portion of the main supporting post. Fig. 4 shows the same parts in similar elevation, partly in section, with the head turned at right angles 30 to the position shown in Fig. 3. Fig. 5 is a side elevation of the lumber jack with another embodiment of stacking device which may be used to facilitate the forming of higher piles of lumber. Fig. 6 is a side elevation of the latter embodiment of my lumber jack showing the method of attaching it to the pile of lumber. Fig. 7 is a plan view 35 of the parts shown in Fig. 6.

Like characters of reference designate 40 corresponding parts in all figures.

10 designates an upright supporting post, the size, shape and construction of which are not essential except that it should be suitably mounted upon a portable stand. 45 For example, I have shown in the drawings a straight vertical post arising vertically from the center of a base 11 and with which it is further connected by means of braces 12.

In the upper end of the post 10 is driven 50 a bushing 13, preferably of metal, which is provided with a central vertical bore. Into this bushing fits the round shank 21 of a contact head 20. A shoulder 22 is formed at the upper end of the shank which limits 55 its downward movement, but allows for its free rotation. The lower end of this shank

is preferably carried down below the end of the bushing and provided with a pin 23 which will prevent the upward movement of the head so that it will not be easily removed 60 from the rest of the apparatus and lost.

It is by giving the upper portion of the contact head the shape which is illustrated in the drawings that this device is peculiarly adapted to the uses for which it is 65 designed and has great advantages over former constructions. Above the shoulder 22 the head is flared out to form a flat body portion 24 of approximately the width of the planks or other material with which it 70 is to be used. The top of this body portion is tapered off to form a straight horizontal edge which is cut away to form a plurality of teeth 25.

The other embodiment of my stacking device shown in Fig. 5 is to be used when the pile of lumber is of such height as to make the stacking impracticable for the workman, and consists in the preferred form of the support 34 formed substantially as shown, 75 carrying at its outer end a contact head 24 similar to that shown in Figs. 3 and 4. Pivotedly connected to the other end of the support 34 is the clenching member 35 formed with the notched end 36. At any 80 convenient place below the contact head 24 a collar 37 with the lug 38 thereon is secured to the arm 34. Engaging this lug is the hooked end 39 of a brace 40, the other end of which is constructed to form a spike 41 85 back of which is an enlarged head 42. The spike is to be driven into the edge of one of the planks in the lumber pile by a hammer blow on the head 42.

The manner in which this apparatus is to 90 be used and its operation are best seen by referring to Figs. 1, 2 and 5 in which 30 designates a pile of planks or boards which may be in a car or wagon, or on the ground, and 31 designates another pile of similar 95 lumber on which these planks are to be stacked. The lumber jack is placed in a desired position. One of the planks is then drawn from the pile 30 onto the jack over the contact head into some such position as 100 that shown at 32. In doing this the head automatically assumes a position with its toothed upper edge transverse to the plank, so that the latter may be teetered upon the jack until it assumes any desired angle of 105 inclination without tipping sidewise. The teeth 25 engage with the under surface of 110

the plank and prevent it from slipping downward. The plank is thereby supported by the jack at different angles of inclination with a considerable amount of stability. Now the planks may be rotated as indicated by the curved arrow in Fig. 2, and at the same time its upper end may be raised until it assumes the position in which it is shown in broken lines at 33. Now it may be shoved up onto the pile 31. This operation may be repeated, or if desired, it may be reversed.

When the height of the pile has reached the point where it is impracticable for the workman to reach such a height, the other embodiment of my stacking device above described may be used. The notched member 35 is forced in between two planks bringing the upright portion 43 of the support 34 against the ends of the boards in the lumber pile, the brace 40 is secured approximately in a horizontal plane, to a plank of the pile 41. It will be readily seen that the device is now firmly mounted, and that, by the operator pulling out a plank as at 44 to stand on, the pile may be increased in height to any desired limit.

It will be understood that this embodiment of my lumber jack may also be used by the operator working on the ground.

My improved jack may be similarly used in loading or unloading cars or wagons, or in changing the position of a lumber pile, and with it one man may handle lumber which, without it, would require the services of several men. In these ways large amounts of work may be accomplished with a minimum amount of labor.

This device is especially designed for handling lumber and this particular use of it has been specifically described. Obviously, however, it may be put to any other similar uses to which it is applicable.

What I claim is,

1. A device of the class specified comprising a portable support having a smooth vertical hole therein, and a contact head having a spindle loosely fitting said hole and rotatably held in an upright position thereby, a shoulder on said spindle arranged to maintain the relation of the spindle in

the support at the same longitudinal position, said contact head having an upper straight engaging edge at right angles to the spindle.

55

2. A device of the class specified comprising a portable support, a contact head pivotally supported therein, and means for preventing upward or downward movement of the head, said contact head having a straight horizontal upper edge provided with teeth.

60

3. A device of the class specified comprising a portable rigid support and a bushing in the upper end thereof, and a contact head having a body portion, a shank depending therefrom through the bushing, a pin through said shank, and an upper straight edge at right-angles to said shank and provided with teeth.

70

4. A device of the class specified comprising a portable rigid support, and a metallic bushing affixed in the upper end of said support; and a rotatable contact head having a body portion, a shank depending therefrom through the bushing, a pin through said shank below the bushing, and an upper horizontal straight edge provided with teeth.

75

5. A device of the class specified comprising a portable support, means for holding said support in a rigid position, and a rotatable contact head supported therein, said contact head having an upper straight edge at right angles to the axis of its rotation.

80

6. A device of the class specified comprising a portable rigid support, means for holding said support in a fixed position and a metallic bushing affixed in the upper end of said support; and a rotatable contact head having a body portion, a shank depending therefrom through the bushing and an upper horizontal straight edge provided with teeth and a pin through the shank below the bushing.

85

In testimony whereof I have signed my name to this specification in the presence of two subscribing witnesses.

WILLIAM E. YERKS.
